UNITED STATES PATENT OFFICE.

VERNON GARNER, OF BOSTON, MASSACHUSETTS, ASSIGNOR TO UNITED PRINTING MACHINERY COMPANY, OF BOSTON, MASSACHUSETTS, A CORPORATION OF MAINE.

SHEET-FEEDING MACHINE.

1,161,933.

Specification of Letters Patent. Patented Nov. 30, 1915.

Application filed July 3, 1914. Serial No. 848,724.

To all whom it may concern:

Be it known that I, VERNON GARNER, a citizen of the United States, and a resident of the city of Boston, in the county of Suffolk and State of Massachusetts, have invented certain new and useful Improvements in Sheet-Feeding Machines, of which the following is a specification, reference being made to the accompanying drawings, which 10 form a part thereof.

My invention relates to sheet-feeding machines in which successive sheets are separated from a bank, or pile, of sheets, and are then automatically carried forward and 15 presented, one at a time, to a printing press, or other machine, which is to operate on such sheets.

The object of my present invention, among other things, is to provide a simple quick- 20 acting and efficient mechanism whereby sheets vertically piled on a horizontal movable board may be separated, one from another, and delivered to the withdrawing rolls which carry the sheets forward to a 25 printing press, or other machine designed to operate on such sheets.

One of the advantages of my mechanism is an increased speed and efficiency in separating the sheets, and presenting them to the 30 withdrawing rolls to be carried forward from my device. Therefore, according to my present invention, the sheets are first combed a short distance in one direction to separate them from the vertical pile, after 35 which they are moved in an opposite direction, and are caught between the withdrawing rolls and so carried from the pile.

In the accompanying drawings, Figure 1 is a side elevation of the essential features of 40 my device; and Fig. 2 is a plan view.

Similar numerals represent similar parts throughout the several figures.

Referring to the figures, 1 is the main frame of a feeding machine which carries a 45 vertically movable board 2 upon which the bank or pile of paper P rests to be fed to my feeder to be separated and carried forward to the press or other machine. The board 2 is raised automatically by means of the vertical screw 3 through mechanism it is not necessary to describe.

4 is a combing roll journaled at 5 at the end of the arm 6 secured to the rock shaft 7 which also carries an upwardly extending 55 arm 8.

9 represents a series of pinions pivotally mounted on the shaft 7 and arm 6, whereby the combing roll 4 is properly rotated as hereinafter described.

The upper end of the arm 8 through its 60 cam roller engages a fan-shaped cam 10 secured to the actuating cam shaft 11 as shown in Fig. 2. To the rock shaft 12 is secured a segmented arm 13 having gear teeth in the ends thereof meshing with the pinion 9, af- 65 fixed to the shaft 7. The swinging move- ment of the arm 13 will therefore cause a rotation of the combing roll 4 so as to carry the top sheet to the left looking at Fig. 1. 14 is another segmented arm affixed to the shaft 70 12, shorter than the arm 13, and having ratchet teeth in its segmented portion.

15 is a heart-shaped cam secured to the cam shaft 11 and operates through the cam roller 16 mounted on the rock lever 17, the 75 rock shaft 12 to give the requisite swinging movement to the segmented arms 13 and 14. The outer end 18 of the rock-lever 17 has pivotally secured thereto the slide rod 19 secured by appropriate brackets in the frame 80 and actuated in an upward direction by the coil spring 20, thereby pressing the oppo- site end of the rock lever 17 with its cam- roller 16 continuously against the cam 15.

21 is the power shaft, rotated in the di- 85 rection of the arrow shown in Fig. 1 by any suitable source of power, and operates through miter gears the cam actuating shaft 11 as shown in the figures.

22 is a trip finger mounted on the rock 90 shaft 23 and has affixed thereto the latch 24 which extends upwardly as shown in Fig. 1.

25 is a pawl pivotally secured to the frame 95 at 26 and adapted to engage with the ratchet teeth in the arm 14; on the inner end of the pawl 25 is the latch block 27 adapted to en- 100 gage with the latch 24 to hold the pawl 25 out of engagement with the ratchet teeth of the arm 14. The spring 28 affixed to the frame and to the outer end of the pawl 25 presses this pawl into engagement with the ratchet teeth of the arm 14, when the trip finger 22 is moved backward by the combed sheet so as to dislodge the latch 24 from the latch block 27. This action stops the rota- 105 tion of the combing roll 4 by causing the arm 13 to cease swinging outwardly simul- taneously with the stoppage of the arm 14 by having the pawl 25 engage with the ratchet teeth in this arm 14. Secured to the shaft 110

29 is the hand operated pinion 30 having its teeth meshing with teeth in the shaft 31 to advance or withdraw the combing roll and trip finger mechanism on the frame 1 according to the size of the sheets which are being separated.

32 are a series of inclined guides pivotally mounted on the frame to direct the top sheet that has been combed (shown in dotted lines) to the trip finger 22.

In operation the cams 10 and 15 are so timed and secured to the shaft 11 as to cause the rotation of the combing roll 4 to separate and carry to the left the top sheet 15 against the trip finger 22 which through the dislodgment of the latch and latch block causes the pawl 25 to engage the ratchet teeth in the arm 14 thereby stopping the rotation of the combing roll 4, after which the 20 cam 10 engages the arm 8 to lift the combing roll 4 from the bank of sheets. Thereafter the trip finger is reset through the pawl 25 being forced downwardly by the outward swing of the arm 14 so as to cause the engagement of the latch 24 with the latch block 27. This movement causes the top sheet to be moved to the left the distance from the edge of the bank to the trip finger 22.

30 Referring to the mechanism to the right of my device looking at Fig. 1, 33 is a roller pivotally mounted on the rock lever 34 journaled on the rock shaft 34^a which is supported by the rock arm 35 mounted on the rock shaft 36. 37 is a roller mounted on the inner end of the rock lever and is adapted to press against the under surface of the parallel bar 38 the inner end of which is pivotally secured to the rock arm 39 journaled on the frame 1, as shown in the figures. 40 is a spring connecting the inner end of the rock lever 34 to the rock arm 35, and tends to hold the roller 37 in close contact with the under surface of the bar 38.

45 Mounted on the rock shaft 36 is the rock lever 41, the upper end of which is pivotally secured to the slide rod 42 secured to the frame 1 and actuated by the coil spring 42^a. To the lower end of the rock lever 41 is se-

50 cured the ratchet bar 43 having the cam roller 43^a adapted to engage the heart-shaped cam 44 secured to the cam actuating shaft 45 which is rotated through miter gears by the power shaft 21. The spring

55 pressed slide rod 42 causes the roller 43^a to follow the heart-shaped cam 44, which so operates the ratchet bar 43 as to cause the roller 33 to catch and push to the right the top sheet which has been separated by the

60 combing roll 4. 46 are a series of guide fingers loosely journaled on the shaft 47 the ends of which rest through gravity on the top of the bank of sheets. The separated sheet as moved to the right by the roller 33

65 passes over the ends of the fingers 46 to the

upper and lower withdrawing rolls 48 and 49, the upper roll 48 being journaled on the rock shaft 50, and the lower roll being journaled on the shaft 51. 52 are the withdrawing belts which carry the separated sheets forward and pass around the pulley 53 mounted on the shaft 54. 55 is a gear affixed to the cam shaft 45 and meshes with the pinion 56 which through the pinion 57 operates the gears 58 and 59 secured to the shafts 51 and 54 respectively to rotate the withdrawing roll 49 and the belt pulley 53. 60 is a trip finger mounted on the rock shaft 61. The latch 62 is also mounted on the rock shaft 61 and is adapted to engage the latch block 63 on the pawl 64 pivotally mounted on the frame so as to engage the ratchet teeth on the bar 43 when the latch 62 is dislodged from the latch block 63. The spring 65 secured to the arm 43 and pawl 64 normally tends to press the pawl 64 into the ratchet teeth of the arm 43. 66 is a rock shaft secured to the frame and has mounted thereon the rock arms 67 and 68, the arm 67 supporting the shaft 50, and the arm 68 supporting the outer end of the bar 38. 69 is a rock arm likewise secured to the rock shaft 66 and carries the cam roller 70 which engages with the fan-shaped cam 71 mounted on the cam shaft 45. This cam 71 imparts the requisite movement to the rock arms 67 and 68 to raise and lower the upper withdrawing roll 48 and the roller 33 on the rock lever 34 through the parallel bar 38 respectively. Mounted on the rock shaft 66 is the rock arm 72 which carries the slotted link 73 which is pivotally secured to the arm 74 mounted on the rock shaft 61. The horizontal movement of the link 73 to the left causes the trip finger 60 to be lifted from the path of the advancing sheet when the withdrawing rolls are acting to grasp the sheet and carry it forward to the belts 52.

In operation, the cams 44 and 71 are so timed and affixed to the shaft 45 that the lever 43 operated by the cam 44 permits the roller 33 through the intermediate parts to push the top sheet to the right and over the guide fingers 46 until the front edge of the sheet is inserted between the withdrawing rolls 48 and 49 and engages the trip finger 60. This trip finger 60 is therefore moved to the right, which movement dislodges the latch 62 from the latch block 63, which causes the pawl 64 to immediately engage the ratchet teeth in the bar 43 through the action of the spring 65, and stops the lateral movement of the roller 33. Meanwhile the cam 71 in its rotation operates the arm 69 which lifts the trip finger from the path of the advancing sheet through the arm 72, slotted link 73, and rock arm 74 mounted on the rock shaft 61 and further the bar 38 presses the roller 37 thereby lift-

ing the sheet roller 33 from the sheets, and then the continuing movement of the cam 71 also lifts the withdrawing roll 48 and allows the trip finger to drop back in operative position by means of the slot in the link 73.

It is apparent, therefore, that increased speed and efficiency in separating and forwarding the individual sheets are attained through my improved feeder for in operation the respective devices are so timed that the combing roll mechanism will be feeding backwardly the second sheet from the bank, as soon as the sheet roller mechanism on the right of Fig. 1 has carried the first sheet sufficiently forward to be caught by the withdrawing rolls and forwarding belts and its back edge is beyond the line of action of the combing roll. By this method of separating and feeding sheets of paper, I am enabled to increase very materially the effectiveness and rapidity in handling banks of paper to be delivered to printing and other like machines.

I claim as my invention:—

1. In a machine for feeding sheets of paper from a pile, the combination with means for operating a combing roll to feed the top sheet in one direction, of means for controlling the combing roll by the sheet, a laterally moving sheet roller mechanism for conveying the top sheet in a direction opposite to the action of the combing roll, and means for controlling the sheet roller by the sheet.

2. In a machine for feeding sheets of paper from a pile, the combination with an intermittently acting combing roll to feed the top sheet in one direction, of means for controlling the action of the combing roll by the sheet, a laterally moving sheet roller mechanism for conveying the top sheet in a direction opposite to the action of the combing roll, and means for controlling the sheet roller by the sheet.

3. In a machine for feeding sheets of paper from a pile, the combination with an intermittently rotating combing roll to feed the top sheet in one direction, of means for controlling by the sheet the rotation of the combing roll between successive operations, and a sheet roller mechanism for conveying at regular intervals the top sheet in a direction opposite to the action of the combing roll, controlled by the sheet.

4. In a machine for feeding sheets of paper from a pile, the combination with an intermittently rotating combing roll to feed the top sheet in one direction, of means for controlling the rotation of the combing roll by the sheet, and a sheet roller mechanism for conveying the top sheet in a direction opposite to the action of the combing roll at regular intervals, controlled by the sheet.

5. In a machine for feeding sheets of

paper from a pile, the combination with an intermittently rotating combing roll to feed the top sheet in one direction, of means for controlling the rotation of the combing roll between successive operations controlled by the sheet, a sheet roller mechanism for conveying the top sheet in a direction opposite to the action of the combing roll, and means for controlling the sheet roller by the sheet.

6. In a machine for feeding sheets of paper from a pile, the combination with an intermittently acting combing roll, of means for raising and lowering the combing roll from the pile, sheet controlled means comprising a ratchet and pawl for throwing the combing roll out of operation, a sheet roller mechanism for conveying the top sheet in a direction opposite to the action of the combing roll, and means for controlling the sheet roller by the sheet.

7. In a machine for feeding sheets of paper from a pile, the combination with means for operating a combing roll to feed the top sheet in one direction, of means for controlling the combing roll by the sheet, a sheet roller mechanism for conveying the top sheet in a direction opposite to the action of the combing roll while the latter acts on the next sheet in the pile, and means for controlling the sheet roller by the sheet.

8. In a machine for feeding sheets of paper from a pile, the combination with means for operating a combing roll to feed the top sheet in one direction, of means for controlling the combing roll by the sheet, a sheet roller mechanism for conveying the top sheet in a direction opposite to the action of the combing roll while the latter acts on the next sheet in the pile, and a sheet operated trip for controlling the sheet roller.

9. In a machine for feeding sheets of paper from a pile, the combination with means for operating a combing roll to feed the top sheet in one direction, of means for controlling the combing roll by the sheet, a laterally moving sheet roller mechanism for conveying the top sheet in a direction opposite to the action of the combing roll between successive operations of the combing roll upon the pile, and means for controlling the sheet roller by the sheet.

10. In a machine for feeding sheets of paper from a pile, the combination with means for operating a combing roll to feed the top sheet in one direction, of means for controlling the combing roll by the sheet, a laterally moving sheet roller mechanism for conveying the top sheet in a direction opposite to the action of the combing roll between successive operations of the combing roll upon the pile, and a sheet operated trip for controlling the sheet roller.

11. In a machine for feeding sheets of paper from a pile, the combination with an

- intermittently acting combing roll, of a sheet roller mechanism for conveying the top sheet in a direction opposite to the action of the combing roll between successive operations of the latter on the pile, means for advancing and withdrawing the sheet roller mechanism along the pile controlled by the sheet, and means for raising and lowering the same from the pile.
- 5 12. In a machine for feeding sheets of paper from a pile, the combination with an intermittently acting combing roll, of a sheet roller mechanism for conveying the sheet in a direction opposite to the action of the combing roll between successive operations of the latter on the pile, means for advancing and withdrawing the sheet roller mechanism along the pile, means for raising and lowering the same from the pile, and
- 10 13. In a machine for feeding sheets of paper from a pile, the combination with an intermittently acting combing roll, of a sheet roller mechanism for conveying the top sheet in a direction opposite to the action of the combing roll before the combing roll acts on the next sheet in the pile, means for advancing and withdrawing the sheet roller along the pile, means for raising and lowering said sheet roller from the pile, and a sheet operated trip for controlling the first of said last-mentioned means.
- 15 14. In a machine for feeding sheets of paper from a pile, the combination with an intermittently acting combing roll, of a sheet roller mechanism for conveying the top sheet in a direction opposite to the action of the combing roll between successive operations of the latter on the pile, means for raising and lowering the sheet roller from the pile at regular intervals, and sheet controlled means comprising a ratchet and pawl for regulating the action of the sheet roller.
- 20 15. In a machine for feeding sheets of paper from a pile, the combination with an intermittently acting combing roll, of a sheet roller mechanism for conveying the sheet in a direction opposite to the action of the combing roll between successive operations of the combing roll on the pile, means for advancing and withdrawing the sheet roller along the surface of the pile, and sheet controlled means comprising a ratchet and pawl for throwing the sheet roller out of operation.
- 25 16. In a machine for feeding sheets of paper from a pile, the combination with an intermittently acting combing roll, of means for controlling the combing roll by the sheet, means for raising and lowering the combing roll between successive operations, a sheet roller mechanism for conveying the sheet in a direction opposite to the action of the combing roll, and means for advancing and withdrawing the sheet roller along the surface of the pile controlled by the sheet.
- 30 17. In a machine for feeding sheets of paper from a pile, the combination with an intermittently acting combing roll, of a sheet operated controlling trip for controlling the action of the combing roll, means for raising and lowering the combing roll from the pile, a sheet roller mechanism for conveying the sheet in a direction opposite to the action of the combing roll between successive operations of the latter on the pile, means for advancing and withdrawing the sheet roller along the pile, and a sheet-operated trip for controlling the advancing and withdrawing means.
- 35 18. In a machine for feeding sheets of paper from a pile, the combination with an intermittently acting combing roll, of a sheet operated controlling trip for controlling the action of the combing roll, means for raising and lowering the combing roll from the pile, a sheet roller mechanism for conveying the sheet in a direction opposite to the action of the combing roll before the combing roll acts on the next sheet in the pile, means for advancing and withdrawing the sheet roller along the pile, means for raising and lowering said sheet roller from the pile, and a sheet operated trip for controlling the first of said last mentioned means.
- 40 19. In a machine for feeding sheets of paper from a pile, the combination with an intermittently acting combing roll, of means for raising and lowering the combing roll from the pile, sheet controlled means comprising a ratchet and pawl for controlling the action of the combing roll, a sheet roller mechanism for conveying the sheet in a direction opposite to the action of the combing roll before the combing roll acts on the next sheet in the pile, means for advancing and withdrawing the sheet roller along the pile, and means for raising and lowering said sheet roller from the pile, the former means being controlled by the sheet.
- 45 20. In a machine for feeding sheets of paper from a pile, the combination with an intermittently acting combing roll, of means for raising and lowering the combing roll from the pile, sheet controlled means comprising a ratchet and pawl for controlling the action of the combing roll, a sheet roller mechanism for conveying the sheet in a direction opposite to the action of the combing roll before the combing roll acts on the next sheet in the pile, means for advancing and withdrawing the sheet roller along the pile, means for raising and lowering said sheet roller from the pile, and a sheet operated trip for controlling the first of said last mentioned means.
- 50 21. In a machine for feeding sheets of paper from a pile, the combination with an intermittently acting combing roll, of sheet

- controlled means comprising a ratchet and pawl for controlling the action of the combing roll, a sheet roller mechanism for conveying the sheet in a direction opposite to the action of the combing roll before the combing roll acts on the next sheet in the pile, means for advancing and withdrawing the sheet roller along the pile controlled by the sheet, and means for raising and 10 lowering said sheet roller from the pile at regular intervals.
22. In a machine for feeding sheets of paper from a pile, the combination with a combing roll intermittently acting upon the 15 top sheet, of means for controlling the combing roll by the sheet, means for advancing the top sheet in a direction opposite to the action of the combing roll between successive operations of the combing roll upon the 20 second sheet, and means for controlling said sheet advancing means by the top sheet.
23. In a machine for feeding sheets of paper from a pile, the combination with a combing roll intermittently acting upon the 25 top sheet, of means for controlling the combing roll by the sheet, means for advancing the top sheet in a direction opposite to the action of the combing roll between successive operations of the combing roll upon the 30 second sheet, and a sheet operated trip for controlling by said top sheet said sheet advancing means.
24. In a machine for feeding sheets of paper from a pile, the combination with 35 means for operating a sheet-feeding device to feed the top sheet in one direction, of means for controlling the sheet-feeding device by the sheet, means for advancing the top sheet in a direction opposite to the action of the sheet-feeding device while the latter acts on the next sheet in the pile, and 40 means for controlling said sheet-advancing means by the top sheet.
25. In a machine for feeding sheets of paper from a pile, the combination with 45 means for operating a sheet-feeding device to feed the top sheet in one direction, of means for controlling the sheet-feeding device by the sheet, means for advancing the top sheet in a direction opposite to the action of the sheet-feeding device while the latter acts on the next sheet in the pile, and 50 a sheet operated trip for controlling by the top sheet said sheet-advancing means.
55. 26. In a machine for feeding sheets of paper from a pile, the combination with means for feeding the topmost sheet rearwardly from the pile, of means for controlling said feeding means by said sheet, means
- for advancing said topmost sheet forwardly 60 off the pile, and means for controlling said sheet-advancing means by said forwardly-moving sheet.
27. In a machine for feeding sheets of paper from a pile, the combination with 65 means for feeding the topmost sheet rearwardly from the pile, a sheet-operated trip for controlling said feeding means, means for advancing said topmost sheet forwardly off the pile, and a sheet-operated trip for 70 controlling said sheet-advancing means.
28. In a machine for feeding sheets of paper from a pile, the combination with 75 means for feeding the topmost sheet rearwardly from the pile, of means for controlling said feeding means by said sheet, means for advancing said topmost sheet forwardly off the pile, between successive operations of the rearwardly feeding means, and means for controlling said sheet-advancing means 80 by said forwardly-moving sheet.
29. In a machine for feeding sheets of paper from a pile, the combination with 85 means for feeding the topmost sheet rearwardly from the pile, a sheet-operated trip for controlling said feeding means, means for advancing said topmost sheet forwardly off the pile between successive operations of the rearwardly feeding means, and a sheet-operated trip for controlling said sheet-ad- 90 vancing means.
30. In a machine for feeding sheets of paper from a pile, the combination with 95 means for feeding the topmost sheet rearwardly from the pile, of tripping mechanism comprising a ratchet and pawl for controlling said feeding means by said sheet, means for advancing said topmost sheet forwardly off the pile, and tripping mechanism comprising a ratchet and pawl for control- 100 ling said sheet-advancing means by the sheet.
31. In a machine for feeding sheets of paper from a pile, the combination with 105 means for feeding the topmost sheet rearwardly from the pile, of tripping mechanism comprising a ratchet and pawl for controlling said feeding means by said sheet, means for advancing said topmost sheet forwardly off the pile between successive op- 110 erations of the rearwardly feeding means, and tripping mechanism comprising a ratchet and pawl for controlling said sheet-advancing means by the sheet.

VERNON GARNER.
